CLUTCH PLATE

Harold Nutt, Chicago, Ill., assignor to Borg-Warner Corporation, Chicago, Ill., a corporation of Illinois

Application October 2, 1944, Serial No. 556,710

5 Claims. (Cl. 192—107)

1

The present invention relates to friction clutches of the type used in motor vehicles and it has particular reference to a clutch plate cushion arrangement for carrying the friction rings that are pressed toward each other for coupling the driving and driven elements of a clutch.

It is one of the principal objects of this invention to simplify the construction of a friction clutch cushion arrangement such as contemplated herein, and to improve the efficiency, operation, and dependability of such arrangement.

It is also a principal object of this invention to provide a cushion element with an elongated foot for attachment to the supporting disc so that the foot extends along a greater peripheral portion of the disc than has heretofore been possible with prior arrangements. This permits the attaching means or rivets to be widely spaced from each other, and also the use of a cushion member having considerable radial length upon a relatively small diameter mounting, thus reducing to a minimum the shearing movement on the attaching rivets or other means.

A further principal object hereof is to provide the cushion members with attaching feet that overlap the feet of the adjacent or proximate members, thereby reducing the total number of rivets and the operations required to anchor all of the cushions on the disc which is due to the fact that the overlapped feet portions will require only one rivet at each overlapped region.

Another object resides in providing a novel foot portion upon a cushion, such foot portion on a given cushion being longer than the peripheral space upon the mounting disc between the cushion at the sides of the given disc.

Still another object hereof is to provide the attaching feet of the cushions with laterally offset toe portions thereby to accommodate such toes to their overlapping arrangement when mounted on the disc.

A still further object is to provide a clutch plate cushion member of generally rectangular shape that comprises a body portion or wing having a flat radial region preferably adjacent one edge and a bowed region of greater extent than the flat region, a narrow neck at the flat region of the wing, and an elongated foot extending lateral to the neck for anchoring the cushion member on the mounting plate, there being an elongated relatively narrow recess between the foot and the bowed region of the wing. In the present arrangement the outer or peripheral margin of the cushion has a segmental contour and the side margins are straight and par-

2

allel to each other. The straight margin at one side of the body which extends toward the neck is provided with an oblique portion extending inward to the recess to accommodate and lie substantially parallel to the straight side edge of the adjacent cushion member.

Additional objects, aims, and advantages of the invention contemplated herein will be apparent to persons skilled in the art after the construction and operation of the friction clutch cushion arrangement is understood from the within description. It is preferred to accomplish the numerous objects of this invention and to practice the same in substantially the manner hereinafter fully described and more particularly as pointed out in the claims. Reference is made to the accompanying drawing that forms a part hereof, wherein:

Fig. 1 is a transverse section of portions of 20 a friction clutch showing the instrumentalities of the present improvement thereon, the view being taken on the plane of line 1—1 of Fig. 2;

Fig. 2 is a fragmentary face view or plan showing the arrangement of the cushion members on 25 the clutch plate improvement viewed on the plane of line 2—2 of Fig. 1;

Fig. 3 is a sectional view on line 3—3 of Fig. 2; and

Fig. 4 is a sectional view on line 4—4 of Fig. 2. 30 The drawing is to be understood as being more or less of a schematic character for the purpose of disclosing a typical or preferred form of the improvement contemplated herein. In the drawing like reference characters identify the same parts in the different views.

In the embodiment of the present invention shown in the drawing, the clutch plate assembly comprises a hub 10 splined to a rotatable shaft and having a radially projecting flange 11 to which an annular mounting plate or disc 12 is anchored by bolts or rivets 13. A series of relatively light-weight cushion members 14, preferably of yieldable material such as sheet metal, are secured by means of rivets 15 to the margin 45 of the mounting plate.

A cushion member comprises a plate of generally rectangular shape that has a flat region 16 extending in a radial direction from its anchored edge. The remaining portion of the cushion plate is bowed as at 17 to provide a freely disposed wing element of concavo-convex section.

The cushion members are adapted to carry the friction creating members 18 and 19 of ring-like 50 form that are mounted upon opposite sides of

the cushion members. As seen in Fig. 1 the friction member 18 is secured to the flat region 16 of the cushion member by rivets 20 that are arranged in a substantially radial row, and the friction member 19 is secured to the bowed body portion 17 by rivets 21 that are arranged in a plane approximately parallel with the plane of rivets 20. By reason of the arrangement described, the cushion member carries the ring 18 on one side and the ring 19 upon its opposite side, with the bowed portion 17 of the cushion tending to urge the rings away from each other so that the friction creating rings will yieldingly respond to lateral pressure exerted against them.

The friction ring 18 lies close to the radial surface of a flywheel or other driving element 22 and the ring 19 is adapted to be yieldably moved in the direction of the flywheel when the pressure plate or other driving element 23 of the clutch moves longitudinally of the shaft. Thus the clutch plate assembly constitutes the intermediate or driven elements of the friction clutch.

As will be seen in Fig. 2, the cushion member 14 has a generally rectangular contour with parallel side edges 24 and 25 that are approximately radially disposed, and the outer margin 26 is an arc that is struck from a radius at the axis of hub 10.

The inner or mounting portion of the cushion is formed with an elongated arcuate foot 27 connected to the wing portion by a neck 28. The side edge 25, as it approaches the foot portion, or about midway its length, is formed with an oblique portion 25a so that this latter portion of the edge extends inwardly of the wing and terminates at the recess 29 that is formed in the cushion member to provide the neck 28. Preferably the neck has a width that is coextensive with the width of the radial flat region 16 upon the cushion member.

The elongated arcuate foot 27 is mounted in overlying relation to the margin of the mounting disc 12 and it is anchored to the disc by rivets 15 that pass through spaced aligned holes in the foot and the disc. The toe of the foot is offset as clearly shown at 31 to permit the toe of a cushion member to be overlapped with the heel portion of the proximate cushion member with the respective holes in register so that a single rivet 15 is employed to anchor these overlapped portions of two cushions to the mounting disc. When mounted in this manner, it will be seen the oblique portion 25a at the left-hand edge of a cushion will lie close to and in substantially parallel relation to the straight left-hand edge 24 of the next cushion. This arrangement disposes the outer corner regions 32 and 33 of adjacent cushions in close relation to each other. Also, it will be apparent that the superficial area of the series of cushions is materially increased over such areas as are provided in prior structures, and this is accomplished without sacrificing the strength or dependability of the cushion members. Furthermore, the main body portions or free wings of the assembled cushions lie close to each other, and a dependable and more rigid mounting is effected due to the elongation

of the feet so that they have overlapped end portions which are connected to the mounting disc by one rivet and a single riveting operation.

While I have described my invention in connection with one specific embodiment thereof, it is to be understood that this is by way of illustration and not by way of limitation and the scope of my invention is defined solely by the appended claims which should be construed as broadly as the prior art will permit.

I claim:

1. A friction clutch plate cushion element of substantially rectangular shape that comprises a wing portion having a flat radial region adjacent a side edge and a bowed region of greater extent than the flat region, the side edges of said wing having parallel portions and one of said edges having an inwardly extending oblique portion; a narrow neck portion forming a continuation of the flat wing region; an elongated foot portion extending lateral to said neck portion for effecting anchorage of the cushion element on a support; and an offset region at an end of said foot portion.

2. A friction clutch plate cushion element as defined in claim 1 wherein the offset portion of the foot comprises a toe at the end of the foot remote to the neck and positioned beyond the adjacent end of the oblique edge portion of said wing.

3. A friction clutch plate comprising a mounting disc; cushion elements arranged in annular array on the peripheral region of said disc, said cushion elements each embodying a wing portion having a flat radial region adjacent one edge and a bowed region of greater extent than said flat region, the side edges of said wing having parallel portions and one of said side edges having an inwardly extending oblique portion; a narrow neck portion forming a continuation of said flat radial wing region; an elongated foot portion extending lateral to said neck portion in overlying relation to the peripheral region of said disc; an offset region at an end of said foot portion overlapping the foot portion of an adjacent cushion element; anchoring means passed through said disc and the overlapping regions of the cushion elements; and friction facings on opposite sides of said cushion elements, one of said facings secured to the flat radial regions of said cushion elements, and the other of said facings secured to the bowed regions of said cushion elements.

4. A friction clutch plate as defined in claim 3 wherein the offset region of the foot comprises a toe at the end of the foot remote to the neck and positioned beyond the adjacent end of the oblique edge portion of said wing.

5. A friction clutch plate as defined in claim 3 wherein the bowed region of the wing is spaced radially outward from the periphery of the disc; and the offset region of the foot comprises an apertured toe at the end of the foot remote to the neck and beyond the adjacent end of the oblique edge portion of said wing.

HAROLD NUTT.
